MULTIPLE PENDULUM TOY

Maurice S. Kanbar, 4 E. 77th St.,
New York, N.Y. 10021

Filed June 17, 1969, Ser. No. 17,749

Term of patent 14 years

Int. Cl. D21—04

U.S. Cl. D34—15

FIG. 1 is a perspective view of my design for a multiple pendulum toy;

FIG. 2 is a front elevational view of the toy;

FIG. 3 is one end-view of the toy, the other end representing the same view; and

FIG. 4 is a top plan view of the toy.

I claim:

The ornamental design for a multiple pendulum toy, as shown and described.
